METHANOL EXTRACTION OF LOW-
TEMPERATURE TAR

Metro D. Kulik, Pittsburgh, Pa., assignor to Consolidation Coal Company, Pittsburgh, Pa., a corporation of Pennsylvania

Filed Mar. 30, 1960, Ser. No. 18,694

3 Claims. (Cl. 208—22)

This invention relates to a process wherein an initial solvent treatment is used for fractionating the liquid products obtained by the low-temperature pyrolysis of naturally occurring carbonaceous solids. It is particularly concerned with the initial selective solvent treatment of primary low-temperature tar with aqueous methanol under selected conditions.

When naturally occurring carbonaceous solid fuels, such as bituminous coal and lignite, are subjected to low-temperature carbonization, i.e., at a temperature below 1400° F., the product tar is collected as a vapor. Subsequent condensation of the vapors produces a highly viscous liquid tar product that is variously designated as primary, whole, unprocessed, unrefined, raw or crude tar. The term "primary tar" is ordinarily applied to tar obtained at low temperatures where a maximum yield of tar is obtained with a minimum of tar decomposition or alteration. These conditions represent an ideal state, and consequently no tar can be said to be entirely primary. As used herein, the terms "primary," "whole," and "raw" are considered essentially synonymous to indicate that substantially all of the low-temperature tar obtained as a liquid product by condensation of the tar vapors is initially subjected to a solvent treatment process as described herein, and is not fractionally distilled prior to this solvent treatment. This tar product contains virtually all of the condensable ingredients of the carbonization vapors along with entrained finely divided particles of coal and partially carbonized coal. The recovery of valuable constituents contained in the tar is of considerable commercial importance. The process of this invention enables the recovery of these valuable constituents from low-temperature tar, whether derived from low rank non-coking coals, e.g., lignite, brown coal and subbituminous coals, or from high-volatile highly caking coals, e.g., Pittsburgh seam bituminous coal.

Where the tar is obtained by a low-temperature carbonization process under fluidized conditions, additional problems of recovery are presented. First, the finely divided particles of coal and partially devolatilized coal contained in the fluidized low-temperature tar are unusually small in size and are present in greater quantity because of the attrition and entrainment caused by the turbulent conditions prevailing within a fluidized low-temperature carbonation processing vessel. Such tars may contain 25 percent or more by weight of finely divided particles of coal and partially carbonized coal. Second, the tars obtained from fluidized low-temperature carbonization processes tend to be of a more primary character, i.e., the tar constituents tend to be closely related in structure to the constituents of the coal that is carbonized because there is little opportunity for cracking the constituents prior to recovery. Hence these tars tend to be more viscous than other types of low-temperature tars.

2

Various techniques and plans have been proposed for processing primary tar for recovery of the valuable liquid constituents therein. All of these plans suffer from certain drawbacks. In some, operability is achieved at the expense of significant tar yield. In others, fractional distillation of the tar, reducing its primary character, results in the cracking of the more valuable constituents to yield less valuable constituents that may be obtained more economically from other sources. In still other methods, relatively expensive solvents are required in large volumes in treating the tar in order to avoid gumming and plugging of equipment and associated operability problems. In yet others of these plans, attempts have been made to first remove finely divided particles present by use of conventional mechanical separation techniques such as filtration, centrifugation and settling. Such techniques have been generally found lacking with respect to operability and commercial feasibility, particularly where a high percentage of solids is present in the tar. In general, the foregoing plans either introduce additional processing steps that are frequently costly and hence of laboratory interest only, or significantly alter the basic characteristics of the tar, whereby a lesser amount of valuable liquid products is recovered.

25 Fractional distillation has been principally used heretofore to effect an initial fractionation of the primary tar. By "topping" of the tar, the more volatile tar acid oils may be recovered therefrom as an overhead distillate. However, depending on the nature of the tar and the thermal treatment, many of the tar constituents may polymerize, decompose or be carbonized. As a consequence, valuable liquid constituents present are lost by conversion to simpler hydrocarbons of less value or to coke.

Because of the highly complex chemical composition 35 of primary low-temperature tar, the initial treatment of the whole tar by selective solvent techniques to effect separation of the valuable constituents of the tar has been considered too difficult to be of commercial importance. Direct solvent treatment of the whole tar must overcome problems of high tar viscosity, poor miscibility of the tar with most solvents, and prolonged period of contact required between the tar and solvent for complete extraction and separation of components, together with high solvent to tar ratios. Ordinarily, any finely divided solids present must first be removed to prevent 40 plugging of the equipment. Emulsification and agglomeration occurring in the tar-solvent system further interfere with operability. Also, the lack of selectivity of various solvent systems used introduces the further problem of after-recovery of sought-for constituents from both 45 the extract and the reject phases of the solvent system. In addition, solvent techniques suitable for high-temperature tar are not ordinarily applicable to low-temperature tar because of the considerably different physical and chemical properties. At present, then, no satisfactory 50 technique of commercial utility is known for the initial solvent treatment of primary low-temperature tar. Where the low-temperature tar is produced under fluidized conditions, the problem of separation becomes even 55 more difficult.

Accordingly, it is an object of the present invention to provide a process for the fractionation of primary tar free from the disadvantages heretofore known.

It is a further object to fractionate tar by an initial

solvent treatment into useful acidic and neutral tar fractions.

It is yet another object to provide a method for the continuous countercurrent extraction of low-temperature tar obtained by the low-temperature carbonization of bituminous coal under fluidized conditions.

In accordance with the broad aspects of this invention, a primary low-temperature tar is treated in a continuous countercurrent liquid-liquid extraction system, including one or more extraction zones, with an aqueous methanol solvent under critical extraction conditions to achieve operability whereby the tar is fractionated into acidic and neutral tar fractions.

The general use of wood alcohol for extracting oils from high-temperature coal tar at room temperature is known. See U.S. 1,327,271. However, the conditions required in the present process for the effective fractionation of primary low-temperature tar into acidic and neutral tar fractions are highly critical in order to achieve operability and fractionation of commercial importance. This solvent fractionation produces tar fractions having distinctive chemical properties and boiling ranges. For achieving effective continuous countercurrent extraction of primary low-temperature tar, the process has been found highly critical with respect to the following factors: contact conditions between the tar and aqueous methanol, aqueous methanol concentration, temperature range, pressure range, and maintenance of the methanol as continuous phase. To attempt to achieve somewhat comparable results in a batch process would require use of excessive solvent to tar ratios, long contact times, and prohibitive settling times. Also, it would be difficult to achieve a separation of the sharpness with respect to chemical properties and boiling ranges characterizing the acidic and neutral tar fractions obtained in the present process.

The process of this invention is generally suitable for the treatment of tars obtained by the pyrolytic decomposition of carbonaceous solids at temperatures below 1400° F. Such carbonaceous solids include all ranks of coal, such as bituminous, sub-bituminous, brown coal, lignite and the like. This process is uniquely adapted to the treatment of low-temperature tars obtained by the low-temperature carbonization of bituminous coals, e.g., high-volatile caking bituminous coals, under fluidized conditions. The resulting tars contain varying amounts of finely divided solids and are ordinarily particularly difficult to treat without substantial loss of valuable constituents.

It is considered critical for the purposes of this invention that the aqueous methanol used as solvent contain from 55 to 95 weight percent methanol with the balance water. Aqueous methanol containing between 55 and 65 percent by weight methanol is preferred where it is desired to maximize the content of tar acids in the acidic tar fraction and minimize the content of neutral oils in this fraction. At above 65 weight percent methanol concentration, substantially all the tar acid oils appear in the acidic tar fraction. Maximum operability and selectivity are obtained when the methanol concentration of the solvent is between 65 and 80 percent by weight. When the aqueous methanol contains less than 55 percent by weight methanol, emulsification occurs and phase separation becomes unobtainable. When the methanol concentration in the solvent exceeds 80 percent by weight, selectivity begins to fall off, with the acidic and neutral tar fractions becoming less sharply defined.

The achieving of satisfactory contact between the solvent and tar is considered critical for obtaining satisfactory operability in a continuous countercurrent extraction process. Various systems are known for achieving continuous countercurrent liquid-liquid extraction. For example, a horizontal multistage contactor may be used with highly viscous liquids such as tars. In general, columns containing packing are to be avoided because of impedance to proper flow of the tar and interference with the maintenance of suitable phase separation. Because

of the characteristics of low-temperature tar, it has been found that an extraction column using a rotating disk contactor is particularly suitable for obtaining the required continuous countercurrent extraction efficiency while maintaining the required phase separation. By use of a rotating disk contactor column, a high plate efficiency can be attained, thereby rendering the process commercially feasible inasmuch as only from 0.5 to 3 volumes methanol per volume of tar is required for efficient countercurrent extraction while still maintaining the methanol as continuous phase.

Many types of columns have been used in liquid extraction processes, such as packed columns, spray columns, baffle columns, and perforated plate columns. However, but few of these columns are suitable for use with highly viscous tars. For the purposes of this invention, to achieve desired operability, an extraction column that has been found particularly suitable contains internal serrated rotating stirrers and stator plates to provide alternating mixing and settling sections whereby effective contact is obtained between the tar and aqueous methanol. Various rotating-shaft extraction columns are known and may be used. However, because of the physical characteristics of the low-temperature tar, it is preferred that the settling or calming sections of such columns be free from packing and thus be in unobstructed communication with the mixing sections. In operating the rotating disk contactor column, a rotor speed providing a peripheral disk velocity of between 0.5 and 5 feet per second is preferred. Where the rotor speed falls below the preferred range, there is poor contact between the tar and aqueous methanol with relatively low extraction efficiency. At higher speeds, emulsification occurs with consequent poor phase separation. An extraction efficiency obtained with from 10 to 20 sections is suitable. Elimination of packing in the calming sections has not been found to deleteriously affect plate efficiency. At the same time this eliminates interference with the ready transport of solids by the countercurrently flowing liquids. Ease of transport is particularly important where there is a substantial amount of finely divided carbonaceous solids present in the tar.

The temperature at which contact occurs between the aqueous methanol and tar is critical in that temperatures below 40° and above 80° C. are unsuitable. Where the temperature in the column falls below 40° C., the tar becomes gummy, cannot be extracted, and plugs the column. As the temperature is raised above about 60°, phase separation becomes poorer as a result of emulsification occurring, with consequent loss of efficiency. Above 80° C., phase separation is substantially lost. In general, optimum results are obtained at a temperature between 40 and 55°.

Because of the low boiling point of the methanol and the critical temperature requirements, effective extraction is carried out at superatmospheric pressure, generally at a pressure of at least 30 pounds per square inch gauge (p.s.i.g.). Where the pressure falls below 30 p.s.i.g., there is a tendency for the methanol to boil, with consequent interference with phase separation. Pressures above about 60 p.s.i.g. do not provide proportionately improved operability and thus are not warranted.

For the purposes of this invention, to achieve the separation of the substantially whole tar into the sought-for acidic and neutral tar fractions, only a single solvent, namely aqueous methanol is used for effecting the initial fractionation. This fractionation is successfully achieved even where finely divided carbonaceous solids are additionally present in the tar. However, where an excessive amount of finely divided solids is present, these may be removed by agglomerating them by a prior solvent treatment of the tar, followed by filtration, as shown in U.S. 2,774,716.

In lieu of agglomeration and filtration, operability may be forced with a highly viscous heavily solids-laden tar by adding a methanol-insoluble high-boiling neutral oil

to this tar. This oil acts as a diluent for the methanol-reject phase of the tar, and also as a carrier for the solids present in this reject phase, thereby effectively increasing the fluidity of this phase. The diluent oil may be autogeneratedously derived from the tar itself during the over-all process.

For a more complete understanding of this invention, its objects, features and advantages, reference should be had to the accompanying drawings in which:

FIG. 1 is a schematic illustration of the process of fractionating primary tar by an initial aqueous methanol treatment into acidic and neutral tar fractions.

FIG. 2 is a fragmentary perspective view of a section of a preferred rotating disk contactor column for use in this process.

FIG. 3 is a schematic illustration of a preferred process for separating the primary tar into acidic and neutral tar fractions together with the further processing of these fractions.

Referring to FIG. 1, low-temperature tar in a storage vessel 1 is fed, preferably under pressure, to the top of a pressurized rotating disk contactor column 2 through a valved conduit 3. Aqueous methanol contained in a storage vessel 4 is fed to the bottom of column 2 through a valved conduit 5. Both the downwardly fed tar and the upwardly fed aqueous methanol are preferably preheated to the extraction temperature used. A geared variable drive motor 6 connected to a rotor shaft 7 of the rotating disk contactor is used to control the rotor speed in the column. Mounted on rotor shaft 7 are rotor disks 8. These are arranged in alternating relation to stator plates 9, which are fastened to the inner wall of column 2. The pressure in the system is measured by a gauge 10.

In a preferred embodiment, the aqueous methanol consisted of 65 weight percent methanol with the balance water, and its flow and that of the tar was regulated so that approximately 1.5 volumes of aqueous methanol was used for each volume of tar fed. The pressure was maintained at 40 p.s.i.g. throughout the run. The extraction temperature was maintained at approximately 45° C. The temperature within column 2 was controlled by the combined use of Nichrome heating coils and the circulation of cooling water through copper tubes surrounding the column (not shown). Throughout the run, the rotor speed was held constant at 450 r.p.m., which corresponded to a peripheral disk velocity of approximately 1 foot per second. It was found that at this rotor speed both good dispersion and separation of the discontinuous tar phase were obtained, the aqueous methanol constituting the continuous phase. The tar feed rate and the methanol to tar volume ratio were controlled so as to prevent flooding of the column during the continuous counter-current extraction. The total duration of a typical run was approximately 6 hours.

Again referring to FIG. 1, the aqueous methanol extract is removed from the top of column 2 through a valved conduit 11 and fed to a distillation column 12. The tar reject phase is removed from the bottom of column 2 through a valved conduit 13 to a flash still 14. The overhead distillate from flash still 14 is fed through a conduit 15 to join the aqueous methanol extract stream. The neutral tar fraction from still 14 is removed as a bottoms product through a conduit 16. The methanol of the extract phase is removed by distillation in column 12 as an overhead product through a conduit 17 and fed to storage vessel 4 for reuse in the process. Make-up aqueous methanol of suitable concentration may be fed through a conduit 18 to vessel 4. The bottoms product from the methanol distillation, which consists of the acidic tar fraction, is removed through a conduit 19. The acidic tar fraction may also be further processed in the same still or elsewhere for removal of valuable tar acid constituents contained therein, as shown in FIG. 3. The neutral tar fraction may also be used directly for commercial purposes as a low-oxygen-containing asphalt.

In FIG. 2 is shown a fragmentary perspective view of a section of one type of rotating disk contactor column found suitable for the continuous countercurrent extraction of whole low-temperature tar using aqueous methanol. Stator plates 20 are rigidly affixed to the inner shell 21 of the column. The rotor disks 22, attached to a shaft 23 and rotatable therewith, preferably have serrated edges. This shape was found to provide more efficient contacting between the whole tar and the aqueous methanol than more conventional smooth-edged disks. No packing is present within the column. A suitable column was made of stainless steel, 1.0-inch inside diameter, had a spacing of 2.5 inches between stator plates and included 27 stages of extraction compartments. This column was 15 electrically heated, with an upper 4-foot section wound with Nichrome heating wire and also with copper tubing for the passage of coolant.

In FIG. 3 is illustrated the further processing of the acidic tar fraction and neutral tar fraction to obtain valuable products for use in commerce. The process in its initial stages corresponds to that illustrated in FIG. 1, and similar numerals have been used for corresponding parts in both figures. Referring to FIG. 3, the aqueous methanol extract from the top of column 2 is led by means of 20 a valved conduit 11' to a fractionating still 24. As the temperature is gradually raised in this still, which is operated at atmospheric pressure, methanol is the first product evolved. This may be fed by means of a conduit 17' to the aqueous methanol storage tank 4 for reuse in the 25 process. A second selected higher-boiling fraction (tar acid oil) consists of the tar acids and neutral oils boiling between about 160 and 300° C. of which, as shown below, more than 50 weight percent boils above 300° C. Various processes may be used for refining this tar acid 30 oil to recover the phenolic constituents therefrom. One such suitable procedure is shown in U.S. 2,666,796. Or if the upper boiling point of this second fraction is set at about 230° C., this fraction will consist principally of the low-boiling tar acids. The neutral oil and high-boiling 35 tar acids will be collected together with the creosote fraction. This creosote fraction, which is the next fraction evolved, consists principally of both liquid and solid hydrocarbons and may contain appreciable quantities of the higher boiling tar acids. It has a continuous boiling range 40 of at least 125° C. beginning at about 200° C. or higher. Creosote is principally used in the preservative treatment 45 of wood structures as protection against attack by fungi, marine borers, or insects. The bottoms residue from fractionating still 24 is designated as an acidic asphaltene or acidic pitch. This material may be used as a binding 50 material or as a road and roofing surfacing agent, or may be further upgraded by treatment with various chemicals such as oxygen, sulfur and chlorine.

The following distribution of tar components, in parts 55 by weight, was obtained in a typical run. Referring to FIG. 3, 100 parts by weight of tar, calculated on a solids-free basis, was fed through conduit 3 to column 2. The methanol extract from the top of column 2 through conduit 11' contained 47.5 parts of tar. The tar reject fed 60 to still 14 contained 52.5 parts tar. An additional 5.2 parts tar, obtained as an overhead distillation product from still 14, was fed through conduit 15 to still 24. The tar acid oil fraction, topped at 300° C., contained 24.2 parts; the creosote fraction contained 17.2 parts; and the acidic asphaltene residue amounted to 11.3 parts by weight of the starting tar.

As further shown in FIG. 3, the neutral tar fraction residue obtained from flash still 14 is fed by means of a conduit 16' to a coker vessel 25 where this fraction is 70 destructively distilled. Evolved gas and light oil constitute the first fraction collected, and the light oil may be readily separated from the gas by condensation. The light oil is a low boiling distillate which contains small amounts of benzene, toluene and xylenes, the principal constituent being referred to as solvent naphtha. The 75

light oil may be used without further purification for solvent purposes. The next fraction which may be recovered is a heavier oil boiling above about 300° C. This oil finds particular utility as a low-oxygen content carbon black feedstock for yielding a high abrasion resistance carbon black. The bottoms residue recovered from coker 25 consists essentially of coke and contains any finely divided particles originally present in the tar. This material is suitable as a fuel for metallurgical and power generation purposes. The coking operation is preferably carried out under conditions which minimize coking of the neutral hydrocarbon liquid products.

The following examples, arranged in tabular form, further illustrate the process of this invention with respect to the conditions desired for its practice and the results obtained therein, but are not intended as limitations thereof.

As may be noted from the data shown in Tables I and II, the yield of extract increases with increasing temperature and with increasing methanol concentration of the aqueous methanol solvent. Also, as shown in Table I, tar acid concentration in the extract decreases with increasing methanol concentration. The ultimate analyses shown in Table IV clearly demonstrate the significant difference in oxygen content obtained between the acidic extract and neutral reject tar fractions.

As has been described herein, an improved method has been provided for the continuous countercurrent frac-

tionation of primary low-temperature tar by an initial solvent treatment using aqueous methanol under selected conditions. However, it is readily apparent that various modifications may be made without departing from the spirit of this invention. For example, in the subsequent distillation treatment of the acidic tar fraction, the tar acid oils may be distilled at various temperatures between 160 and 300° C. At lower boiling cuts, the creosote fraction will be enriched with increasing amounts of neutral oils. Other such modifications will readily suggest themselves. Thus while this invention has been described with respect to specific preferred embodiments, it is not to be limited by the illustrative examples given but its scope should be determined in accordance with the objects and claim thereof.

The embodiments of the invention in which an exclusive property or privilege is claimed are defined as follows:

1. An acidic tar extract consisting essentially of a portion of a low-temperature tar initially dissolved and extracted at a temperature between about 40 and 55° C. by a single solvent consisting of an aqueous methanol solution containing about 60 to 70 weight percent methanol, said tar being obtained from the low temperature carbonization of bituminous coal, said extract containing about 80 to 95 percent by volume of tar acids and more than 50 weight percent of said extract boils above 300° C.

2. An acidic tar extract consisting essentially of a portion of a low-temperature tar dissolved and extracted at a temperature of 45° C. by an aqueous methanol solution containing 65 weight percent methanol, said tar being obtained from the low-temperature carbonization of bituminous coal, said extract containing about 80 to 95 percent by volume of tar acids and about 54 percent by weight of said extract boiling above 300° C.

3. A two-phase liquid-liquid extraction process for the continuous countercurrent fractionation of primary low-temperature tar into acidic and neutral tar fractions by an initial treatment of said tar with a single solvent consisting of aqueous methanol,

said tar being produced by the carbonization of high-volatile bituminous coal under fluidized conditions at a temperature below 1400° F. and containing finely divided particles selected from the class consisting of coal and partially devolatilized coal, comprising:

feeding said tar as a first liquid phase downwardly in a liquid-liquid extraction zone containing mixing sections,

feeding as initial single solvent for said tar an aqueous methanol solution as a second liquid phase containing 60 to 70 weight percent methanol and the balance water upwardly in said zone in countercurrent relation to the tar direction while agitating said tar and aqueous methanol in said mixing sections to provide effective mixing therebetween and while maintaining said tar and aqueous methanol at a temperature between 40 and 55° C. at a pressure between 30 and 60 p.s.i.g. and the low-temperature tar

as dispersed liquid phase in the aqueous methanol as continuous liquid phase, the feed rates of the low-temperature tar and aqueous methanol being regulated so that between 0.5 and 3.0 volumes of aqueous methanol are fed to said zone for every volume of said tar, whereby the two phases are separated into an aqueous methanol extract and reject, recovering the aqueous methanol extract containing the acidic tar fraction from the upper end of said zone, 10 and

recovering as aqueous methanol reject the remainder of said tar as the neutral tar fraction from the lower end of said zone.
